(57) **CLAIM**

The ornamental design for a cue tip shaper and scuffer, as shown and described.

DESCRIPTION

FIG. 1 is a top front left side perspective view of a first embodiment of a cue tip shaper and scuffer showing my new design in a closed position;

FIG. 2 is a front perspective view thereof; showing the cup tip shaper and scuffer in an open position;

FIG. 3 is a top front perspective view in an alternate position;

FIG. 4 is a top front bottom perspective view of FIG. 1 thereof;

FIG. 5 is top front rear perspective view thereof;

FIG. 6 is a left bottom perspective view thereof;

FIG. 7 is a right bottom perspective view thereof, in a rotated position;

FIG. 8 is a top front left perspective view of the second embodiment; and,

FIG. 9 is a top front left perspective view thereof showing the cup tip shaper and scuffer in an open position; the only difference between the first and second embodiments are the shape of the scalloping at the bottom side, and the double lines on the circular joint.
